ANTI-JIMMY LOCK

Joseph F. Skorepa, New York, N. Y.

Application May 29, 1934, Serial No. 728,070

19 Claims. (Cl. 70—29)

This invention relates to improvements in anti-jimmy locks and more particularly to the kind having a curved or semi-circular bolt which may be used with swing doors or with sliding doors.

5 An object of the invention is to provide novel mechanism, in a lock, which may be operated either by a knob or a key, or both, which is strong, durable and secure and which prevents dislocation of the bolt, casing or the keeper, from the exterior of the door, by means of a jimmy or any other tool.

A feature of the invention relates to novel means cooperating with the bolt to lock it in its effective and ineffective positions.

15 Another feature of the invention relates to means including an element to lock the bolt locking means, or in other words prevent displacement of the bolt locking means.

20 A further feature of the invention relates to novel means for actuating the locking element to unlock the bolt locking means and to then actuate the latter to unlock the bolt so that it may be actuated at will by suitable key operated or knob operated means.

25 Still another feature of the invention relates to novel means, including a settable finger piece, whereby the key operated means may be locked at will to prevent the operation of the lock by the key.

30 Other features and advantages will herein-after appear.

In the drawings which form part of the specification,

Fig. 1 is a sectional top plan view taken on the line 1—1 of Fig. 2;

Fig. 2 is a vertical section taken on the line 2—2 of Fig. 1;

Fig. 3 is a detail view of the bolt;

Fig. 4 is a perspective view of one of the locking devices for the bolt;

Fig. 5 is a view similar to Fig. 2 showing the parts moved sufficiently to actuate the locking element located between the two locking devices which cooperate with the bolt and showing also the locking devices withdrawn from the bolt to unlock the latter;

Fig. 6 is a view similar to Figs. 2 and 5 but showing the bolt moved to its ineffective position and secured in said position by the locking devices;

Fig. 7 is a vertical section taken on the line 7—7 of Fig. 5 showing the keeper and the bolt therein; and

Fig. 8 is a vertical section taken on the line 8—8 of Fig. 2.

Similar reference characters represent similar parts throughout the several views.

The lock 10 includes a casing 11, Fig. 1, which is secured to a door 12 by screws 13. The casing has a stud 14 upon which is pivotally supported a semi-circular bolt 15 by means of an arm 16, see Figs. 3 and 8 also. The arm 16 is provided with a tongue 17 engaging in a groove 18 and is secured to the bolt by a screw or rivet 19. The arm 16 also has a hub 20 through which extends 10 a flattened portion 21 of a sleeve 22 which is rotatably supported on the stud 14 for the purpose of actuating the bolt 15, in a manner hereinafter described, to move it to its locking or effective position, Figs. 1 and 2, or its ineffective 15 position in Fig. 6.

The bolt in its effective position extends through two apertures 24 in a wall 25 of the casing 11 and through two apertures 26 of a wall 27 of a keeper 28, said keeper being secured 20 to the door frame by screws 30 passing through a flange 31 and screws 32. The portion 33 of the keeper wall 27, between the apertures 26, is segmental and is embraced by the bolt 15.

The bolt is normally locked against actuation 25 from either of its positions. For this purpose it is provided with two notches 35 extending into the bolt from its concaved face, Figs. 2, 3 and 8, and in which notches engage lateral extensions 36, see Fig. 4 also, of cooperative locking devices or 30 slides 37. These slides 37 are moved, by suitable means hereinafter described and including actuating levers 38, to their ineffective positions, Fig. 5, to carry the lateral projections 36 out of the notches 35 and thus unlock the bolt prior 35 to its rotative movement. The locking slides 37 are guided in slots 40 formed by the wall 25 and ribs 41 formed on the casing. They are held in the slots 40 by the actuating levers 38 which are connected thereto by studs 38a. 40

The lock may be operated to actuate the bolt, by a small knob or finger piece 41 from the inside of the door or by means of a key operated means 42 from the outside of the door. The finger piece 41 has a shaft or spindle 43, extending into the casing, and carries a sleeve 44 secured thereto by a pin 45. Secured to one end of the sleeve is a cam disc 46 which is rotatable with the knob 41. The cam disc 46 has thereon two cam notches 47 in which studs or 50 rollers 48 of the levers 38 normally lie. Upon the rotation of the disc 46 the rollers 48 ride out of the notches 47, as in Fig. 5, and on to the dwell 49 of said disc, thus actuating the levers 38 about fulcrums 50, against the action of return 55

springs 51 supported on studs 51^a, to move the locking slides to their ineffective position, or in other words out of the notches 35 of the bolt 15 to unlock the latter.

5 After the bolt 15 has been thus unlocked, as in Fig. 5, it is rotated by means, operated by the knob actuated shaft 43 and now to be described, to the position in Fig. 6. On the sleeve 44 there is secured a pinion 52 which drives an intermediate gear 53 to rotate a pinion 54, secured to the sleeve 22 in any convenient manner, to thus rotate the bolt 15, which, it will be remembered, is connected to said sleeve 22 by the arm 16. When the cam disc 46 has made one half revolution the rollers 48 move into the notches 47, under the action of the springs 51, which springs actuate the levers 38 to move the locking devices 37 to cause their extensions 36 to move into the notches 35 and thus again lock the bolt as in Fig. 6.

20 The key operated means 42 includes the usual tumbler barrel or cylinder 55 in which there is contained mechanism operable by an insertable key to rotate a flat spindle 56 extending into a transverse slot 58 formed in a hub 59 suitably secured to an arm 60 to rotate the latter. The arm 60 has a pin 61 which extends into a slot 61^a of the cam disc 46 to rotate the latter from the outside of the door and thus actuate the bolt and its associated mechanism as previously described in connection with the knob 41. The parts 59, 60 and 61 constitute a coupling element which is rotatably supported in a cover plate 62, Fig. 1, secured to the stud or post 14 by a screw 63 and to two other posts 64, Fig. 2, by screws 65. Since it requires only one half revolution of the disc 46 to actuate the bolt 15 and it requires a complete revolution of the key to bring it to a position for withdrawal from the key hole, the slot 62 is elongated and arcuate to permit the pin 60 to move idly through 180° from the position in Fig. 1 to that in Fig. 5, the pin becoming then effective to actuate the disc 46 to the position in Fig. 6.

45 The bolt carrying arm 16 is provided with two stop faces 66, Figs. 2, 3 and 6, which engage the wall 25 of the lock casing to arrest the bolt in its two extreme positions and to register the notches 35 with the projections or heads 36 of the locking devices 37.

50 To hold one of the locking devices 37 in its normal, locking position to prevent shifting thereof and thus make it more difficult to pick the lock, there is provided a locking element 70 55 a tooth 71 which is normally in the path of a tooth 72 of the lower locking device or slide 37 there being a slight space between the set of teeth 71 and 72 to permit a slight movement of the slide, for a purpose hereinafter described, but not sufficient to dislodge said locking element from the notch 35 in the bolt. Said element 70 is rotatably supported on the sleeve 22 and it has a notch 73 into which extends a tooth 74 of an arm 75 secured to the other locking device 37. 60 Upon the initial inward movement of the upper slide 37 the arm, through the medium of the tooth 74, actuates the locking element 70 to the dot-and-dash line position in Fig. 2 to carry the teeth 71 out of the path of the teeth 72 of the lower locking slide 37 and thus permitting the lower slide 37 to be moved with the upper slide to its ineffective position, Fig. 5. There is sufficient play between the teeth of the gears 52, 53 and 54 to permit movement of the cam disc 46 and the actuation of the locking element 70 to

its unlocked position before the rotation of the bolt 15 starts.

The operation, of the bolt 15 and its associated mechanism, is similar to that above described, when the bolt is to be moved from the position in Fig. 6 to its locking position in Fig. 2, except that the shaft 43 is moved in a counter clock-wise direction.

To set the lock so that it cannot be actuated by the key from outside the door, the sleeve 44 is provided with a flange 76 having therein a notch 77 into which may be moved a tooth 78, of a slide 79, by pulling rightwardly, Fig. 1, on a finger piece or button 80 secured to the slide 79. The slide is provided with a slot 81 through which extend the knob shaft 43, and a boss 81^a, on the casing 11, to support and guide said slide. The intermediate gear 53 is also supported on the boss 81^a and is held on a reduced portion 81^b thereof by a plate 82 secured by screws 83 threaded into bosses 84 on the casing 11. The slide 79 is held in either of its two positions by a detent 85, secured to the casing 11 by a screw or rivet 86 and engaging in either one of two notches 87 in the slide 79.

25 It will be understood that the lock is constructed so that it may be readily and quickly assembled.

While certain preferred embodiments of the invention have been shown and described, it will be understood that changes in the form, arrangement, proportions, sizes and details thereof may be made without departing from the scope of the invention as defined in the appended claims.

35 I claim:—

1. In a lock, the combination of a casing, a semi-circular bolt to cooperate with a keeper, a pivot to support said bolt in said casing, actuating means to drive said bolt about its pivot 40 from its projected position to its retracted position and vice-versa, cooperative means to lock said bolt in either of its positions, auxiliary means to lock the cooperative means, and means operable by the actuating means to actuate the auxiliary means to unlock said cooperative means and to then withdraw the cooperative means from the bolt to unlock the latter, the actuating means being then effective to actuate said bolt.

50 2. In a lock, the combination of a casing, a semi-circular bolt to cooperate with a keeper, a pivot to support said bolt in said casing, actuating means to rotate said bolt from its projected position to its retracted position and vice-versa, said bolt having two notches, a slide to engage in either notch to lock the bolt in either of its positions, a guideway for said slide, and means operable by the actuating means to withdraw the slide from the notch and then actuate said bolt, the last mentioned means including a cam, and a lever operable by said cam, said lever engaging said slide to actuate it, and to keep it in its guide way.

60 3. In a lock, the combination of a casing, a semi-circular bolt to cooperate with a keeper, a pivot to support said bolt in said casing, actuating means to rotate said bolt from its projected position to its retracted position and vice-versa, said bolt having two notches, a slide 70 to engage in either notch to lock the bolt in either of its positions, an auxiliary element to prevent movement of said slide out of the engaged notch, means operable by the actuating means to actuate said slide, and means whereby 75

- the initial movement of said actuating means is effective to actuate said auxiliary element to thus permit movement of said slide to unlock said bolt.
5. 4. In a lock, the combination of a casing, a reentrant bolt, a support for said bolt on said casing, means to actuate said bolt from a locking position to a non-locking position and vice-versa, cooperative means to lock said bolt in its locking position, auxiliary means to lock the cooperative means, and means operable by the actuating means to actuate the auxiliary means to unlock said cooperative element and to then withdraw the cooperative means from the bolt to unlock it, the actuating means being then effective to actuate said bolt.
5. In a lock, the combination of a casing, a reentrant bolt, a support for said bolt on said casing, means to actuate said bolt from a locking position to a non-locking position and vice-versa, said bolt having two notches, a slide to engage in either one of said notches to lock the bolt in either one of its positions, a guideway for said slide, and means operable by the actuating means to withdraw the slide from the notch and then actuate the bolt, the last mentioned means being also effective to prevent said slide against working itself out of its guide way.
6. In a lock, the combination of a casing, a rotatable prime mover supported in said casing, a semi-circular bolt, means independent of the prime mover to rotatably support said bolt in said casing, a cooperative element to lock said bolt, an auxiliary element supported on the pivot of said bolt to hold the locking element in its active position, a cam secured to said prime mover, means operable by said cam to actuate said auxiliary element to render it ineffective during the early part of the actuation of the cam, and gearing connecting the prime mover with the bolt so that the latter may be rotated by the prime mover after it has been unlocked.
7. In a lock, the combination of a casing, a rotatable prime mover supported in said casing, a semi-circular bolt, means independent of the prime mover to rotatably support said bolt in said casing, two cooperative elements engaging said bolt on opposite sides of its support to lock said bolt, a cam secured to said prime mover, means operable by said cam to actuate said cooperative elements simultaneously to unlock said bolt, and means connecting the prime mover with the bolt so that the latter may be rotated by the prime mover after the bolt has been unlocked.
8. In a lock, the combination of a casing, a semi-circular bolt to cooperate with a keeper, a pivot to support said bolt in said casing, actuating means to rotate said bolt from its projected position to its retracted position and vice-versa, cooperative means to lock said bolt in either position, auxiliary means to lock the cooperative means, means operable by the actuating means to actuate the auxiliary means to unlock said cooperative means and to then withdraw the cooperative means from the bolt to unlock the latter, the actuating means being then effective to actuate said bolt, and means to lock the actuating means to prevent the actuation of said bolt thereby.
9. In a lock, the combination of a casing, a semi-circular bolt to cooperate with a keeper, a pivot to support said bolt in said casing, key operated means to rotate said bolt from its projected position to its retracted position and vice-versa, said bolt having two notches, a slide to engage in either notch to lock the bolt in either of its positions, a guide for said slide, means operable by the key operated means to withdraw the slide from the notch and then actuate said bolt, and means settable at will to lock the key operated means to prevent the actuation of said bolt thereby.
10. In a lock, the combination of a casing, a reentrant bolt, a support for said bolt on said casing, means to actuate said bolt from a locking position to a non-locking position and vice-versa, cooperative means to lock said bolt in its locking position, auxiliary means to lock the cooperative means, means operable by the actuating means to actuate the auxiliary means to unlock said cooperative element and to then withdraw the cooperative means from the bolt to unlock it, the actuating means being then effective to actuate said bolt, and means to lock the actuating means to prevent the actuation of said bolt thereby.
11. In a lock, the combination of a casing, a rotatable prime mover supported in said casing, a semi-circular bolt, means independent of the prime mover to rotatably support said bolt in said casing, a cooperative element to lock said bolt, an auxiliary hub element supported on the pivot of said bolt to hold the locking element in its active position, a cam secured to said prime mover, means operable by said cam to actuate said auxiliary element to render it ineffective during the early part of the actuation of the cam, gearing connecting the prime mover with the bolt so that the latter may be rotated by the prime mover after it has been unlocked, and means cooperating with the prime mover to lock it and thus prevent the actuation of said bolt thereby.
12. In a lock, the combination of a casing, a rotatable prime mover supported in said casing, a semi-circular bolt, means independent of the prime mover to rotatably support said bolt in said casing, a cooperative element to lock said bolt, an auxiliary element supported on the pivot of said bolt to hold the locking element in its active position, a cam secured to said prime mover, a lever operable by said cam to actuate said auxiliary element, means connecting the cooperative element with the auxiliary element so that the latter may be actuated to render it ineffective during the early part of the actuation of the cooperative element, gearing connecting the prime mover with the bolt so that the latter may be rotated by the prime mover after it has been unlocked, and locking means to prevent the actuation of said cam and also prevent the actuation of said bolt.
13. In a lock, the combination of a casing, a rotatable prime mover supported in said casing, a semi-circular bolt, means independent of the prime mover to rotatably support said bolt in said casing, a cooperative element to lock said bolt, a cam secured to said prime mover, a lever operable by said cam to actuate said cooperative element, gearing connecting the prime mover with the bolt so that the latter may be rotated by the prime mover after it has been unlocked, and means settable at will to lock said gearing and thus prevent the actuation of said bolt by the prime mover.
14. In a lock, the combination of a casing, a rotatable prime mover supported in said casing, a semi-circular bolt, means independent of the prime mover to rotatably support said bolt in said casing, a cooperative element to lock said bolt, a cam secured to said prime mover, a lever operable by said cam to actuate said cooperative

element, gearing connecting the prime mover with the bolt so that the latter may be rotated by the prime mover after said bolt has been unlocked, a locking member connected to said prime mover, a slide to engage said locking member to thus lock the prime mover to prevent the actuation of said bolt thereby, a finger piece to actuate the slide to render it effective, and a detent to engage said slide to hold it in either of its positions.

15. In a lock, the combination of a casing, a semi-circular bolt, means to rotatably support said bolt on said casing, said bolt having two oppositely disposed notches in the concaved face thereof, two devices, one engaging in each notch to lock said bolt, an element to prevent displacement of one of said devices, actuating means to render said element ineffective and to withdraw the devices from the notches in said bolt to unlock it, means to actuate said bolt after it has been unlocked, and means operable at will to lock the actuating means.

16. In a lock, the combination of a casing, a semi-circular bolt, means to rotatably support said bolt on said casing, said bolt having two oppositely disposed notches in the concaved face thereof, two devices, one engaging in each notch to lock said bolt, an element to prevent displacement of one of said devices, actuating means to render said element ineffective and to withdraw the devices from the notches in said bolt to unlock it, and means to actuate said bolt after it has been unlocked.

17. In a lock, the combination of a casing, a semi-circular bolt to cooperate with a keeper, a pivot to support said bolt in said casing, actuating means supported on said casing to rotate

said bolt from its projected position to its retracted position and vice-versa, two devices co-operating with the bolt to engage opposite ends thereof to lock it in both positions, and means operable by the actuating means to move said devices out simultaneously of cooperative relation with said bolt to unlock the latter so that the bolt may be operated by said actuating means.

18. In a lock, the combination of a casing, a reentrant bolt, a support for said bolt on said casing, means to actuate said bolt from a locking position to a non-locking position and vice-versa, two devices cooperating with said bolt to lock it in either one of its positions, said devices being also effective to relieve the support of any strain in either position of the bolt which strain may result from an attempt to force the bolt, and means operable by the actuating means to move said locking devices simultaneously out of cooperative relation with said bolt to unlock the latter so that it may be operated by the actuating means.

19. In a lock, the combination of a casing, a reentrant bolt, a support for said bolt on said casing, means to actuate said bolt from a locking position to a non-locking position and vice-versa, two devices cooperating with said bolt to lock it, said devices being also effective to relieve the support of any strain which may result from an attempt to force the bolt, an element cooperating with one of said devices to lock it, and means operable by the actuating means to actuate said element to unlock the device with which it operates and to then actuate said devices to unlock the bolt.

JOSEPH F. SKOREPA.
